CLAIM

The ornamental design for an illuminated box, as shown and described.

DESCRIPTION

FIG. 1 is a left side view of the illuminated box showing an embodiment of my new and ornamental design;

FIG. 2 is a right side view thereof;

FIG. 3 is a front side view thereof;

FIG. 4 is a rear side view thereof;

FIG. 5 is a top side view thereof;

FIG. 6 is a bottom side view thereof;

FIG. 7 is a perspective view thereof;

FIG. 8 is a perspective view thereof, with the "3D" logo removed for illustration purposes; and,

FIG. 9 is a perspective view thereof; with a surface removed for illustration purposes.

The portions indicated in broken lines are for illustrative purposes only and form no part of the claimed design.
